Attorney's

UNITED STATES PATENT OFFICE.

WOODFORD SHANNON, OF LOUISVILLE, KENTUCKY.

DISPLAY-RACK.

968,201.

Specification of Letters Patent. Patented Aug. 23, 1910.

Application filed August 18, 1909. Serial No. 513,449.

To all whom it may concern:

Be it known that I, WOODFORD SHANNON, a citizen of the United States, residing at Louisville, in the county of Jefferson and State of Kentucky, have invented certain new and useful Improvements in Display-Racks, of which the following is a specification.

The present invention relates to display racks of that type intended for displaying mattresses, and has for its purpose to provide such a device of knock-down construction, and which when assembled may be readily transported from place to place.

15 The essential purpose of the invention is in providing the display rack with carriages with means for permitting their withdrawal for almost their full length for placing in position the springs or mattresses to be displayed, or for removing them, said carriages being adapted to slide in and out to exhibit the goods.

20 The further advantage of the construction is such that the supports or tracks for the carriages may be adjusted relatively to each other so that the highest box mattresses or the smallest springs may be readily accommodated within the minimum of space.

25 With these as the special advantages the invention embodies other points of novelty which will be pointed out in the course of the following extended description and set forth in the appended claims.

30 In the accompanying drawings which show the preferred embodiments of the invention:—Figure 1 is a perspective view of the display rack complete. Fig. 2 is a horizontal sectional view of a carriage and guide rail, Fig. 3 is a diagrammatic illustration 35 showing the disposition of the corner posts of the frame, Fig. 4 is a detail view showing the disposition of the slots in the forward and rear corner posts, Fig. 5 is a transverse sectional view taken along the line 3—3 of Fig. 2, looking in the direction of the arrow, Fig. 6 is a front elevation of a guide rail and a forward end of a carriage, Fig. 7 is a perspective view of a modified form of display rack, Fig. 8 is a horizontal sectional 40 view corresponding to that shown in Fig. 2, Fig. 9 is a diagrammatic view corresponding to Fig. 3, Fig. 10 is a view corresponding to Fig. 4, and, Fig. 11 is a transverse sectional view taken along the line 5—5 of Fig. 8, looking in the direction of the arrow.

Referring to the several figures in detail, and wherein like numerals of reference indicate corresponding parts in the different views shown, the invention comprises a framework of angle bars of which the numerals 1 indicate the lower side members, 2 the end members, 3 the upper side bars, and 4 the upper end bars. The side bars of each of these sections are oppositely disposed, *i. e.*, their grooved portions are turned outwardly, while the corresponding portions of the end bars thereof are turned inwardly. They are assembled in this relation by the corner plates 5'. Connecting the upper and lower sections are the corner posts 5 and 6 disposed in precisely that manner shown in Fig. 3; and for securing the same in position a plurality of corner plates 7 are provided. The supporting frame is fitted with casters 4' whereby the display rack may be transported about the room.

The several parts just enumerated constitute the frame structure and their manner of assembling is such that the several parts constituting the same are adapted to be disconnected, to effect which ordinary screw threaded bolts 8' are used for holding the structure intact.

The opposite faces of the corner posts 5 and the corresponding portions of the rear posts 6 are each provided with a plurality of peculiarly shaped slots 7', each slot being substantially a circular opening and having a narrow extension projecting tangentially therefrom as distinct from the ordinary "key-hole" slots wherein the narrow extension projects diametrically from the circular opening as is the case in mattress display cabinets of a known type, and the disadvantages of which type will be referred to hereinafter. From the illustrations it will be observed that the slots in the forward corner posts are arranged in substantially vertical position and with their enlarged or circular portions disposed to the rear, while on the rear posts the tangential portions of the slots are disposed horizontally and with the circular or enlarged openings toward the top. The advantage of this relative arrangement will presently be made clear.

The function of the slots is that of providing a means for adjustably and securely supporting the several guide rails or tracks 8 of which there are two for each mattress.

supporting carriage. Each of the tracks 8 comprises an angle bar on the vertically disposed portion of which and at each end is a headed stud or bolt 9, the purpose whereof being to engage within the slots 7' as will be obvious by reference to Fig. 1. The heads of the bolts 9 are such as will readily permit their insertion within the circular opening of the slot, whence the shank portion of the bolts may be brought within the tangential groove. And by reason of this manner of connection and having the slots of the front and rear corner posts in right angular relation, there is allowed some spring of the frame body, and ease in adjusting the spacing of the guide rails for the carriages. This peculiar manner of connecting the guide rails as compared to the case wherein the "key-hole" member is adopted is further useful in that in the present instance the studs or bolts engaging the tangential portions of the rear slots will prevent any tendency of the tracks to tilt when the carriages are distended, while in the latter case the withdrawn carriage has a tendency to lift the rear ends of the guide rails by virtue of the key-hole slot connection. The horizontal portions of the guide or supporting rails 8 constitute the tracks proper and at their forward ends they have journaled therein each a roller 10 on which the sliding carriage is adapted to travel.

The mattress supporting carriages are likewise of angle iron construction and comprise a framework of side bars 11, end bars 12, cross bars 13 and three or more tensioning rods 14. The tensioning rods 14 are rigidly secured to the forward angle bar 12 but have spiral springs 15 connecting with the rear angle bar.

The side bars 11 of each carriage are disposed opposite to the tracks 8 whereby the latter provides a support for the former as shown in Figs. 1 and 5; and to readily permit the sliding movement of the carriage upon the tracks the carriage is provided with a pair of rollers 16 journaled within the side bars 11 near their rear ends. It will thus be seen that with the rollers 10 and 16 co-operating in the manner shown in Fig. 2, the mattress supporting carriages may be readily reciprocated in the manner desired and with the minimum amount of friction. To prevent the weight of the mattress or other article supported upon the carriage from tilting the latter when it has been withdrawn, the rear angle bar 12 of the carriage is cut-away to provide a pair of lugs or stops 17 which will engage with the underside of the tracks 8 when a carriage is drawn to such position as mentioned. The cut-away portion of the bar 12 provides the clearance for the track 8, as shown in Fig. 5. And to prevent the carriage being moved too far within the frame the front

bar 12 of the frame is of such width as to engage with the forward ends of the track members 8, in the manner shown in Fig. 6.

Referring to the alternative structure of display cabinet which I have disclosed and which may be preferred under certain conditions it may be stated that the structure is generally of the form of rack above described. The structure now under consideration comprises a supporting frame in all respects similar to that described of Fig. 1 and need not therefore be described here.

The differences lie only in the carriage and track construction to wit: To the under side and at the rear end of each track 8 there is provided an angle piece 18 which constitutes a stop for a projecting piece 19 of which there are two fixed to each carriage. The purpose of the members 18 and 19 is to limit the return movement of the carriage; and the member 19 is further serviceable in that it prevents the carriage being withdrawn too far, in which event the stops 19 engage with the rollers 10. In the present instance, the front and rear angle bars 20 of the carriages are cut-away as shown at 21 to align with the grooved surface of the angle bars 11.

While I have shown and described the details of my invention I would not wish it understood that I have limited myself to the precise structure shown, since it may in certain instances be advisable to make certain changes which will better adapt the invention to the purpose in view; instead I reserve the right to make such changes without departing from the spirit of the invention in question and limit myself only to such disclosures as are made in the prior art to which this invention pertains.

Having thus described my invention, what I claim as new therein and desire to secure by Letters Patent, is:—

1. A display cabinet comprising a frame, slots formed in the frame at its front and rear ends, said slots being respectively disposed in relatively vertical and horizontal positions, tracks provided with members adapted to fit within said slots whereby to detachably mount the same on the frame, a carriage mounted to slide on said tracks, said horizontal slots adapted to prevent tilting of the rear ends of said tracks when the carriage is withdrawn; and means for limiting the sliding movement of said carriage.

2. A display cabinet comprising a frame of angle bars of knock-down construction, horizontally disposed slots formed in the rear vertical posts of said frame, vertically disposed slots formed in the front corner posts of the frame, tracks comprising angle bars provided with headed studs adapted to fit within the slots of the corner posts whereby said tracks are detachably mounted in the frame, carriages mounted to slide on

- said tracks, and means for limiting the sliding movement of said carriages.
3. A portable display cabinet comprising a frame of angle bars and of knock-down construction, slots formed in the corner posts of said frame, said slots comprising each a circular opening having a tangential extension, the slots of the rear corner posts being horizontally disposed, the slots of the front corner posts being substantially vertically disposed, track members comprising angle bars having headed studs adapted to fit and lock within said slots whereby to adjustably and detachably support the tracks within the frame, carriages mounted to slide on said tracks, means preventing the tilting of the carriages when the same are withdrawn, and means for limiting the sliding movement of said carriages.
- 10 4. A portable display cabinet comprising a frame of angle bars of knock-down construction, rollers on which said frame is mounted, slots formed within the corner posts of said frame, the slots of the rear

corner posts being disposed at right angles 25 to the slots of the front corner posts, angle bars providing track members, each of said track members provided with studs adapted to fit within the slots whereby the tracks are adjustably and detachably supported in the 30 frame, carriages supported on and adapted to slide on said tracks; said supporting means comprising roller bearings journaled in the forward ends of the tracks and supporting the carriage, and roller bearings 35 journaled in the rear end of the carriage and supported on said tracks; means carried by the carriages to prevent tilting of the same when the carriages are withdrawn, and means for limiting the sliding movement of 40 said carriages.

The foregoing specification signed at Louisville, Kentucky, this sixth day of July, 1909.

WOODFORD SHANNON.

In presence of two witnesses—

FRANCES MAULL,
STELLA TOLAN.
